UNITED STATES PATENT OFFICE.

JOHN J. McCARTHY, OF MIDDLEBORO, MASSACHUSETTS

PIPESTEM CLEANER.

Application filed July 18, 1923. Serial No. 652,246.

To all whom it may concern:

Be it known that I, JOHN J. McCARTHY, a citizen of the United States, residing at Middleboro, in the county of Plymouth and State of Massachusetts, have invented new and useful Improvements in Pipestem Cleaners, of which the following is a specification.

The object of this invention is to provide a cleaner composed of flexible wire and adapted to be inserted in the bore of a tobacco pipe stem which is either straight or curved, and to clean the bore by removing therefrom all matter accumulated therein including the relatively hard caked matter which accumulates in the bore at its junction with the bowl, the construction of the cleaner being such that it is adapted to scrape and remove deposits from all portions of the bore, and ream out caked deposits in the forward end of the bore and the bottom of the bowl.

I attain the object of the invention by the improved construction hereinafter described and claimed.

25 Of the accompanying drawings forming a part of this specification,—

Figure 1 is a side view of a pipe stem cleaner embodying the invention.

Figure 2 is an enlargement of a portion of 30 Figure 1.

Figure 3 is an end view, looking toward the outer end.

Figure 4 shows in perspective portions of the two wire members shown by the preceding figures before said members are intertwined.

Figure 5 is a section on line 5—5 of Figure 2, considerably enlarged.

The same reference characters indicate the 40 same parts in all the figures.

My improved cleaner is composed of two flexible members 12 of flat-sided wire which is oblong in cross section, each member having side faces 13, and edge faces 14, intersecting the side faces, the intersection of said faces forming angular scraping edges or corners 15.

The outer ends of the members 12 are V-shaped, each end being formed by two 50 oblique faces 16 which meet to form an apex 17, on the longitudinal center of the member.

The members in the condition shown by Figure 4, are placed side by side with their inner side faces 13 contacting with each 55 other, and the faces 16 of each member flush with the faces 16 of the other member.

The members are then intertwined between the points 18 and 19, (Figure 1), the point 18 being spaced from the V-shaped ends. The twisting operation provides two-part helical scrapers extending lengthwise of the cleaner, each helical scraper presenting two scraping corners 15, one following the other when the cleaner is rotated in the bore of a pipe stem as shown by Figure 5, in which the bore of the stem is indicated much enlarged by the dotted circle 20. A slight transverse curvature is imparted to the members by the twisting operation, so that the corner 15 of one member is slightly offset from the edge face 14 of the other member, the two corners 15 being thus adapted to act simultaneously in scraping the bore.

The V-shaped ends of the members collectively constitute a two-part reamer, adapted to bore through a caked deposit, the apex of the reamer being on the longitudinal center or axis of the cleaner.

The width of each member 12 is preferably about one-sixteenth of an inch, and its thickness is preferably about one-fourth of its width. These dimensions may be slightly varied, however. I find that a cleaner composed of two members of about the dimensions specified, has sufficient flexibility to conform to any of the usual curves of pipe stems, and is more flexible than would be the case if a single wire member, having the thickness of the two members here shown, were employed. I also find that each member supports the other, so that the cleaner is not objectionably twisted by torsional strain exerted in rotating it in a pipe stem, and relative movement or displacement of the V-shaped ends is prevented.

The members 12 are connected at the inner end of the cleaner by means forming an operating handle.

In this instance the members are two pieces of wire connected at the inner end of the cleaner by a knob or handle 22, to which the pieces are suitably fixed. The members may be parts of a single elongated piece of wire bent at its mid-length to form a neck connecting the members at the inner end of the cleaner.

The cleaner is normally straight, and is therefore adapted for use in a straight stem.

An enclosing tube or sheath 23, shown by dotted lines in Figure 1, may be provided to contain the cleaner when it is not in use,

the sheath being adapted for insertion in a garment pocket. One end of the sheath may be yieldingly engaged with the head or knob 22.

5 The twisted portions of the members 12, held in contact with each other only by the intertwisting of the members, are adapted to slip longitudinally on each other when the cleaner is flexed by contact with a bore 10 of a curved pipe stem, so that the cleaner may be substantially as flexible as one of the members 12 alone.

If desired, however, the V-shaped end portions of the members may be brazed, 5 soldered, or otherwise united to each other, in which case the twisted portion will be less flexible than when the members are free to slip on each other.

I claim:

20 1. A pipe-stem cleaner composed of two flat-sided wire members, each oblong in cross section, placed side by side and intertwisted so that their longitudinal edges

form helical two-part scrapers extending lengthwise of the cleaner, each scraper presenting two scraping corners, one following the other when the cleaner is rotated in a pipe stem, the outer ends of said members being V-shaped, and flush with each other, and forming a two-part pointed reaming 25 cutter, the point of which is on the longitudinal center of the cleaner, the gage of the wire forming said members being such that the cleaner is adapted to enter the bore of a pipe stem and has a sufficient flexibility to 30 conform to curvature thereof, each member supporting the other and confining the said V-shaped ends beside each other.

2. A pipe stem cleaner substantially as specified by claim 1, the twisted portions 40 of said members being free to slip longitudinally on each other.

In testimony whereof I have affixed my signature.

JOHN J. McCARTHY.
